UNITED STATES PATENT OFFICE

139,636

DESIGN FOR AN AUTOMOBILE

George W. Walker, Pleasant Ridge, Mich., assignor to Bohn Aluminum & Brass Corporation, Detroit, Mich., a corporation

Application September 1, 1943, Serial No. 111,049

Term of patent 3½ years

(Cl. D14—3)

To all whom it may concern:

Be it known that George W. Walker, a citizen of the United States of America, residing at Pleasant Ridge, in the county of Oakland and State of Michigan, has invented a certain new, original, and ornamental Design for an Automobile, of which the following is a specification, reference being had to the accompanying drawing, forming a part thereof, wherein:

Fig. 1 is a perspective view of an automobile embodying my new design.

Fig. 2 is a plan view thereof on a reduced scale; and

Fig. 3 is a rear elevational view thereof on a reduced scale.

The side of the design not shown is substantially similar to the side shown in Fig. 1.

I claim:

The ornamental design for an automobile, substantially as shown and described.

GEORGE W. WALKER.
